UNITED STATES PATENT OFFICE.

ARTHUR O. GARRETT, OF SAN DIEGO, AND CHRISTOPHER E. FUNNELL AND WILLIAM L. HOFFMAN, OF LOS ANGELES, CALIFORNIA.

SLOTTING MACHINE.

Application filed December 17, 1920. Serial No. 431,432.

To all whom it may concern:

Be it known that we, ARTHUR O. GARRETT, CHRISTOPHER E. FUNNELL, and WILLIAM L. HOFFMAN, citizens of the United States, residing at San Diego and Los Angeles, in the counties of San Diego and Los Angeles and State of California, respectively, have invented a certain new and useful Slotted Machine, of which the following is a specification.

Our invention relates to a machine for providing a series of parallel slots in any surface and it is more particularly adapted for use in connection with the slots in hard rubber battery plate retainers as set forth in a companion application filed by Arthur O. Garrett, Christopher E. Funnel and William L. Hoffman for storage battery plates, filed December 17, 1920, Serial No. 431,431, and the objects of our invention are: first, to provide a novel machine for providing a series of parallel slots in any flat surface; second, to provide a machine of this class in which a plurality of circular saws are positioned in certain relative position to each other in connection with a supporting means for sawing a plurality of slots at a time in any flat surfaced object; third, to provide novel means for supporting said saws in their certain relation to each other; fourth, to provide means for supporting said saws in connection with the supporting means and adjustable relatively thereto, so that different depth slots may be cut; fifth, to provide a new and novel gang saw mandrel and sixth, to provide a machine of this class which is very simple and economical of construction, durable, easy to operate, adjustable throughout and which will not readily deteriorate or get out of order.

With these and other objects in view as will appear hereinafter our invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a top or plan view of our machine; Fig. 2 is a side elevational view thereof showing the supports fragmen-

tarily; Fig. 3 is an enlarged detailed sectional view through 3—3 of Fig. 2.

Similar characters of reference refer to similar parts and portions throughout the several views of the drawings.

The table member 1, guide 2, supporting brackets 3, braces 4, supports 5, bearing member 6, caps 7, shaft 8, saw blades 9, separating washers 10, washer 11, lock nut 12, collar 13, washer 14, block 15, adjusting screw 16 and sheave 17 constitute the principal parts and portions of our slotted machine.

The table 1 is preferably rectangularly shaped and is provided across the same with a guide member 2 over the upper surface and extending from this guide member part way across the middle thereof is a slot 1^a which is of sufficient width to permit the edges of the saw to protrude through said table for sawing any object on the table. This table may be supported by any means desired. We have shown leg members 1^b with means 1^c for bracing the same. Secured to this table at opposite ends are the brackets 3 positioned on an angle as shown best in Fig. 2 of the drawings and their one ends are supported by means of angular supporting members 5 secured at opposite ends of the table by means of bolts 5^a and these supports 5 are secured to the support 3 by means of bolts 5^b at their upper ends, their lower ends being supported by means of braces 4 which are secured by means of bolts 4^a and by means of screws 4^b screwed into the edge of the table at the upper ends of said braces 4. These supports 3 are each provided with elongated holes 3^a adapted for the bolts 6^a and to permit longitudinal movement on said support 3 by means of said elongated holes. These bolts 6^a support journals consisting of the members 6 and cap 7 which form journals for the main shaft 8. Also mounted on these supports 3 in spaced relation from the bearing member 6 is a block member 15 secured thereto by means of bolts 15^a. This block member 15 is provided in its upper side with a threaded hole adapted for the adjusting screw 16 which is provided with a hexagon portion 16^a adapted to facilitate the turning of the adjusting screw 16 with a wrench and the upper end of this adjusting screw 16 fits into a hole in the lower side of the

100
105

bearing member 6, thus providing means of adjusting the position of the bearing 6 relatively to the supports 3, after which they may be secured tightly by means of 5 the bolts 6^a. It will be noted that there are provided bearings 6, set screws 16 and blocks 15 at each end of the table on supports 3.

The shaft 8 is provided with an enlarged 10 portion 8^a which forms a shoulder 8^b for one of the saw members 9 to rest against. A plurality of these saws are placed in spaced relation on this shaft 10 with one resting against the enlarged portion 8^a and 15 they are held in certain spaced relation to each other by means of washers 10. It will be here noted that these washers 10 may be of different thickness to provide for different width spacing for the saws. The shaft 8 is threaded at 8^c adapted for the nut 12 and between the nut 12 and the saw is provided a washer 11 which is adapted to rest against the side of one of the saws thus providing means for clamping the saws in certain 20 spaced relation to each other, as shown best in Fig. 3 of the drawings. Mounted on this shaft near the bearing at the opposite end is a collar 13 and held on said shaft by means of a set screw 13^a and between this collar 13 and the bearing is a 25 washer 14. It will be noted that between the enlarged portion 8^a and the other bearing at the opposite end is another washer 14^a, thus providing thrust means for preventing the shifting of the shaft in the 30 bearings. This shaft is provided with a sheave 17 upon which may be mounted a belt which extends to any driving mechanism.

40 Though we have shown and described a particular construction, combination and arrangement of parts and portions we do not wish to be limited to this particular construction, combination and arrangement but desire to include in the purview of our invention the construction, combination and arrangement substantially as set forth in the appended claims.

It is obvious that with this construction, 45 there is provided a means for slotting articles by the use of which a series of parallel slots may be readily provided in any flat surfaced object; that the depths of the saw cuts may be regulated to form grooves or slots as desired; that they may be spaced as desired; that there is provided means for supporting the saws in certain spaced relation to each other and clamped so that they will not loosen; that there is provided means

for supporting the object to be sawed and 60 means for guiding said object on said support.

Having thus described our invention what we claim as new and desire to secure by 65 Letters Patent is:

1. A slotting machine, including a table member provided with a slot in the middle thereof, supporting members positioned on an angle at opposite ends of said table, journals adjustably mounted on said supports, a shaft mounted on said journals, a gang saw secured to said shaft positioned so that its edge extends through the slot in said table. 70

2. A slotting machine, including a table member provided with a slot in the middle thereof, supporting members positioned on an angle at opposite ends of said table, journals adjustably mounted on said supports, a shaft mounted on said journals, a gang saw secured to said shaft positioned so that its edge extends through the slot in said table comprising an enlarged portion on said shaft, a plurality of circular saws positioned in spaced relation on said shaft, separator washers for holding said circular saws in certain spaced relation to each other and means for clamping said saws and separating washers together. 80

3. A slotting machine, including a table member provided with a slot in the middle thereof, supporting members positioned on an angle at opposite ends of said table, journals adjustably mounted on said supports, a shaft mounted on said journals, a gang saw secured to said shaft positioned so that its edge extends through the slot in said table comprising an enlarged portion on said shaft, a plurality of circular saws positioned in spaced relation on said shaft, separator washers for holding said circular saws in certain spaced relation to each other, means for clamping said saws and separating washers together and means for revolving 90 said shaft. 95

4. A device of the class described, including a table member provided with a slot therethrough, gang saws positioned so that their edges protrude through said slot and means for adjusting the position of said gang saws relatively to said table. 100 110

In testimony whereof, we have hereunto set our hands at Los Angeles, California, this 30th day of November, 1920.

ARTHUR O. GARRETT.
CHRISTOPHER E. FUNNELL.
WILLIAM L. HOFFMAN.
